DIPPING-MACHINE.

1,015,998.

Specification of Letters Patent. Patented Jan. 30, 1912.

Application filed March 24, 1911. Serial No. 616,682.

To all whom it may concern:

Be it known that I, JOHN W. DENMEAD, a citizen of the United States, residing at Akron, in the county of Summit and State 5 of Ohio, have invented new and useful Improvements in Dipping-Machines, of which the following is a specification.

This invention has relation to improvements in dipping machines and has especial 10 relation to devices to be used in carrying out the manufacture of rubber goods by what is known as the dipping process as contradistinguished from the process of making them by molding.

15 The object of the invention is to provide a device by which a plurality of forms, suitably supported, may be dipped in a siccative solution at determined intervals and after being dipped are raised from the solution 20 and later inverted so that the surplus undried solution will not accumulate at one point on the forms whereby better and evener articles are produced.

A further object is to make the machine 25 substantially automatic, to be operated by a timed shaft so that the intervals between the dipping operation may be regulated as well as the inverting of the forms after each dipping operation, and my invention 30 further contemplates providing an automatic shut-off for the device when the proper time has expired.

With the foregoing and other objects in view, the invention consists in the novel 35 construction, combination and arrangement of parts constituting the invention to be hereinafter specifically described and illustrated in the accompanying drawings which form a part hereof wherein is shown the 40 preferred embodiment of the invention, but it is to be understood that changes, variations and modifications can be resorted to which come within the scope of the claims hereunto appended.

45 In the drawings in which similar reference numerals indicate like parts in the different figures, Figure 1, is a view in side elevation of the device embodying this invention with portions omitted; and, Fig. 2, 50 is a view in end elevation looking from the right of Fig. 1.

Referring to the drawings in detail, the reference numerals 1, 2, 3 and 4 designate four upright parallel posts, each of which

has at its upper and lower ends collars 5 for 55 securing the posts to fixed supports such as the floor and ceiling of a room. These posts usually consist of polished pipes and are arranged at the corners of an imaginary parallelogram. Extending between the posts 60 1 and 2 is a cross-arm 6 provided at its ends with bearings 7 slidably mounted to permit vertical reciprocation between the posts 1 and 2, and between the posts 3 and 4 is a similar cross-arm parallel with the arm 6 65 and provided with end bearings 8 similar to the bearings 7. The inner faces of the cross-arms are provided with a pair of lugs 9 between each of which is secured one of the ends of an upwardly-extending wide yoke 70 10 which forms an arched member and serves to cause the cross arms to reciprocate vertically in unison with each other. Secured to the yoke 10 is an upwardly-projecting strap 11 preferably provided with a rounded central portion 12. Inclosing the rounded portion 12 is a loop 13 the upper end of which is threaded and engages in a threaded opening in one side of a turn-buckle 14 which is provided with pins 15 80 for easy manipulation. Extending from the opposite end of the turn-buckle 14 is a threaded shaft 16 the upper end of which is secured to the lower end of a clevis 17 through the sides of which extends a pin 18. 85

Extending between the posts 3 and 4 is a V-shaped bracket 19 held in position by clamps 20. The rear end of the bracket 19 is bifurcated to provide a pair of ears 21 between which is pivotally mounted one end 90 of an oscillatory arm 22 the opposite end of which is provided with an aperture to receive the pin 18 in the clevis 16. Connected with the extended end of the arm 22 is a rope or cord 23 passing over suitable pulleys 24 to a counter-weight 25 at its opposite end, whereby the weight of the yoke 10 and its connected mechanism is balanced. The 95 arm 22 is further provided with a roller 26 for a purpose to be later described.

Secured in suitable bearings 27 on the posts 3 and 4 is a cross-shaft 28 on which is mounted a cam 29 positioned to engage the under face of the roller 26 for oscillating the free end of the arm 22 for causing vertical reciprocation of the yoke 10 and its connected mechanism. The cam 29 is provided with a cut-out portion 30 to permit the arm

BEST AVAILABLE COPY

22 to lower the yoke 10 when the roller encounters this cut-out portion. The cam 29 is further provided with a raised portion 31 for raising the arm 22 higher than its normal position when the roller 26 is on the main portion of the cam 29. The hub 32 of the cam is provided on its outer face with teeth to constitute one member of a grab-clutch. Mounted on the shaft 28 is a companion clutch-member 33 having one face thereof provided with teeth to engage with the end of the hub 32 and establish clutching relation therewith. The clutch-member 33 is splined on the shaft 28 so as to be longitudinally shiftable thereto and yet be rotated in unison therewith. The clutch-member 33 is shifted into and out of clutching engagement by means of a clutch-lever 34 pivotally mounted on an arm 35 secured preferably to the post 3.

Mounted on the post 4 is a bracket 36 the outer end of which is provided with an aperture to receive a shaft 37 the opposite end of which is supported by a suitable bearing 38 on the post 3 and which is omitted in Fig. 1 to prevent confusion of lines. The shaft 37 is threaded a portion of its distance and is provided inside the bracket with a threaded nut 39 the outer face of which is formed to constitute a sprocket-wheel 40 to receive a sprocket-chain 41 the opposite portion of which passes over a larger sprocket-wheel 42 on the shaft 28. The threaded shaft is revolved by means of a belt applied to the pulley 43. Mounted on the shaft 37 is an adjustable collar 44 arranged when the shaft is shifted longitudinally by means of the nut 39 to engage the clutch-lever 34 and throw it to disengage the clutch-member 33 from clutching relation with the hub 32.

Extending between the cross-bar 6 and the complementary cross-bar between the posts 3 and 4 is a rotatable shaft 45 having fixed securely thereto a plurality of depending brackets 46 to the lower faces of which is attached a plate 47 from which depends a plurality of forms 48 on which the rubber articles are formed from repeated dippings in a siccative solution. Fixedly mounted on the shaft 45 adjacent to the cross-arm 6 is a small spur gear 49. Mounted pivotally on a bolt or pin 50 on the cross-arm 6 is a segmental gear 51 arranged to intermesh with the beveled gear 49. The opposite end of the segmental gear 51 is provided with a friction roller 52 which is adapted to encounter the foot 53 of a bracket 54 secured to the post 1, and positioned to encounter the roller 52 when the yoke 10 and its connected mechanism is raised beyond a certain point and as the roller engages the foot 53 the segmental gear is given a partial rotation which causes a corresponding movement of the gear 49 and the shaft 45 which inverts

the forms 48, at any time when the forms have been raised beyond the point shown in Fig. 1.

Below the plate 47 is a large shallow tank 55 supported at each end by a pair of legs 56. Extending longitudinally below the tank and rotatably mounted in the members of the two pairs of legs are shafts 57 provided intermediate the legs with counterweights 58. Mounted on both ends of the shafts are a pair of upwardly and outwardly curved arms 59, the upward ends of which are bent inwardly over the top of the tank 55 and are secured at the ends to a pair of covers 60. These covers are preferably of thin sheeted aluminum and are arranged to extend to the central line of the tank and there contact to close the tank. I preferably provide on the ends of the arms 59, weights or bars 61. Projecting outwardly from the arms 59 at one end of the tank are pins 62 provided with transverse apertures to freely receive operating rods 63 which are provided at their upper ends with apertured heads 64 pivotally mounted on a lug 65 secured to the inner face of the cross-piece 6. Mounted on the rods 63 are adjustable collars 66 as shown in the drawings.

Assuming that the plate 47 is provided with a plurality of depending forms 48 and the tank approximately filled with a proper siccative solution, the shaft 28 is rotated by means of the pulley 43 and as the roller 26 encounters the depressed portion 30 of the cam 29 the free end of the arm 22 will be lowered causing the forms 48 to approach the top of the tank 55. Simultaneously with the lowering of the cross-arm 6 the rods 63 will be forced downwardly causing the upper collars 66 to encounter the pins 62 and force the arms 59 apart carrying with them the covers 60 so as to uncover the tank to permit the forms 48 to enter. As soon as the roller 26 leaves the depressed portion 30 of the cam the forms will be raised to the position shown in the drawings and the covers of the tank will be returned to their closed position. As soon as the roller 26 encounters the raised portion 31 of the cam the outer free end of the arm 22 will be raised beyond its normal position which causes the cross-arm 6 to rise in unison therewith, in doing which the roller 52 on the segmental gear will encounter the foot 53 of the bracket 54 causing an inversion of the plate 47 with the forms 48 and will hold them in the inverted position as long as the roller 26 is on the raised portion 31 of the cam, which intervals can be easily determined or timed, after which the parts will be restored to the position shown in the drawings.

In view of the fact that the threaded shaft 37 is driven by the shaft 28 the tappet-collar 44 will at a determined time throw the

clutch-lever 34 into its inoperative position to disengage clutching relation between the members 32 and 33 of the clutch. From this will be seen that the parts of the machine will operate easily and automatically and can be started at night after the close of the factory, and the machine will operate itself until the number of dippings required are given, after which, the machine will automatically shut itself off without any further assistance.

I claim:

1. A dipping machine comprising a reciprocally-movable form-bearing member, a tank containing a solution constituting a bath into which the forms are adapted to dip, a closure device for said tank and means operative only when said form-bearing member is shifted and arranged to move said closure member to its open or closed position on the approach and recession respectively of said form-bearing member.

2. A dipping machine comprising a reciprocally-movable form-bearing member, a tank containing a solution into which the forms are adapted to dip, a pair of plates constituting a closure device for said tank, and means operative only when said form-bearing member is shifted and arranged to move said plates to their open position on the approach of said member and to return them to their closed position on the recession of said member.

3. A dipping machine comprising a reciprocally-movable form-bearing member, a tank containing a bath into which the forms are adapted to dip, a pair of plates arranged to constitute a closure device for said tank, a pair of rocking-arms connected with said plates, means connected with said rocking-arms operating to move said plates in unison with the movement of said form-bearing member to cause said plates to move to their open position on the approach of said form-bearing member and to move them into their closed position on the recession of said member.

4. A dipping machine comprising a reciprocally-movable form-bearing member, a tank containing a solution constituting a bath into which the forms are adapted to dip, a plate constituting a closure device for said tank, a rocking-arm connected to said plate, a counterbalance for said closure device, and means connected with said form-bearing member and engaging said rocking-arm operating to move said closure member to its open position upon the approach of said form-bearing member and arranged to return said closure device to its closed position on the recession of said member.

5. A dipping machine comprising a reciprocally-movable form-bearing member, a tank containing a solution constituting a bath into which the forms are adapted to

dip, a plate constituting a closure device for said tank, an arm supporting said plate, a shaft on which said arm rocks, a counterweight for said device and means acting in unison with the movements of said form-bearing member to shift said closure member.

6. A dipping machine comprising a reciprocally-movable form-bearing member, a tank containing a solution constituting a bath into which the forms are adapted to dip, a pair of plates constituting a closure device for said tank, a pair of arms connected with and constituting a supporting medium for said plates, shafts on which said arms are mounted to permit the movement of said plates into and out of their open and closed position, and means operating to shift said plates in unison with the movement of said form-bearing member.

7. A dipping machine comprising a revolute form-carrying member, means arranged to vertically reciprocate said member, means engaging said member and tending to cause a partial revolution thereof, a bath into which the forms carried by said members are adapted to dip and means operative only when said form-carrying member is shifted and arranged to close said bath when said forms are removed therefrom.

8. A dipping machine embodying a supporting instrumentality, a carriage mounted thereon, a form-bearing member on said carriage, a tank containing a solution constituting a bath into which the forms on said form-bearing member are adapted to dip, a closure device on said tank arranged to be shifted from said tank and replaced coincident with the approach and recession of said form-bearing member, and means operative only when said carriage is shifted and arranged to shift said closure device.

9. A dipping machine comprising a supporting instrumentality, a carriage mounted thereon, a revolute form-bearing member mounted on said carriage, a vertically oscillatory arm connected with said carriage for raising and lowering the same, a roller mounted on said arm, a loosely mounted cam engaging said roller, a shaft for said cam, a clutch for operating said cam, automatic mechanism operating to throw said clutch into its inoperative position at a predetermined interval, and a bath into which the forms are adapted to dip.

10. A dipping machine comprising a supporting instrumentality, a carriage slidably mounted thereon, a rotatable shaft on said carriage, a form-bearing member mounted on said shaft, a gear on said shaft, an arm bearing a segmental gear intermeshing with said first gear and pivotally mounted on said carriage, a stop engaging the extended end of said arm during the upward reciprocation of said carriage for partially rotating

4
said form-bearing member, means for vertically reciprocating said carriage and a tank containing a solution constituting a bath into which the forms carried by said member are adapted to dip.

11. A dipping machine embodying a form-bearing member, a tank containing a solution constituting a bath into which the forms carried by said member are to be immersed, 10 a closure device for said tank arranged to be moved to its open position previous to the immersion of said forms and returned to its closed position upon their withdrawal, and means operative only when said form-bearing member is shifted and arranged to shift said closure device.

12. A dipping machine comprising a form-bearing member, a tank containing a solution constituting a bath into which the forms 20 carried by said member are adapted to be immersed, means for producing the immersing of the forms borne by said members in said bath, a closure device for said tank ar-

ranged to be moved to its closed position upon the removal of said forms therefrom, 25 and means operative only when the form-bearing member is shifted and arranged to shift said closure device.

13. A dipping machine comprising a form-carrying member, means for vertically reciprocating said member at predetermined intervals, a tank containing a solution constituting a bath into which the forms carried by said member are adapted to be dipped, a closure device for said tank, and 30 means operative only when said form-carrying member is shifted and arranged to shift said closure device.

35 In testimony whereof I have hereunto set my hand in presence of two subscribing witnesses.

JOHN W. DENMEAD.
